UNITED STATES PATENT OFFICE.

JOHN NUTTALL, OF CHICOOPEE, MASSACHUSETTS, ASSIGNOR TO A. G. SPALDING & BROS., OF JERSEY CITY, NEW JERSEY, A CORPORATION OF NEW JERSEY.

ROLLER-SKATE.

942,344.

Specification of Letters Patent.

Patented Dec. 7, 1909.

Application filed May 21, 1909. Serial No. 497,414.

To all whom it may concern:

Be it known that I, JOHN NUTTALL, a citizen of the United States, residing in Chicopee, Hampden county, in the State of Massachusetts, have invented certain new and useful Improvements in Roller-Skates, of which the following is a specification, reference being had to the accompanying drawings, forming a part hereof.

10 This invention relates to the construction of frames for roller skates and is particularly concerned with the formation of the plates, both toe and heel, including the adjusting and clamping devices, and with the 15 means for securing the trucks to the frames. One object of the invention is to secure great rigidity without increase in weight, and another is to simplify and improve the construction, particularly so as to reduce the 20 number of parts and the number of rivets required to hold the parts together.

Other objects and useful purposes accomplished by the improved construction will appear more clearly in this specification 25 in which the improvements are described with reference to the embodiment thereof shown in the accompanying drawings, in which—

Figure 1 is a top view of the improved 30 skate. Fig. 2 is a longitudinal section on the irregular plane indicated by the broken line 2—2 of Fig. 1 with parts in elevation. Fig. 3 is a view partly in front end elevation and partly in transverse section on an 35 irregular plane, the toe plate and forward extension of the heel plate being in section approximately on the plane indicated by the line 3—3 of Fig. 2, while the toe clamp bracket is shown in elevation as to its right 40 hand end and approximately in central longitudinal section as to the central lug and left hand portion. Fig. 4 is a view in section on the plane indicated by the line 4—4 of Fig. 2, looking in the direction of the 45 arrows, the forward truck and its immediate appurtenances being omitted, while the wheels and shaft are indicated by dotted lines. Fig. 5 is a view in section on the plane indicated by the line 5—5 of Fig. 2, looking in 50 the direction of the arrows. Fig. 6 is a rear end elevation, partly in section on the plane indicated by the line 6—6 of Fig. 2.

Fig. 7 is a detail side elevation of a portion of the forward bracket and its appurtenances with the axle in section. Fig. 8 is a 55 detail view of the toe clamp bracket.

The foot plate, as usual, comprises a rear portion or heel plate *a* and a forward portion or toe plate *b*. Each of these plates may be stiffened by depending 60 flanges, as at *a'* and *b'* respectively. By the present improvements, however, each of these plates is greatly stiffened and strengthened by longitudinal corrugations. The heel plate has in its rearward portion *a*² corrugations *a*³ which are sunken or pressed downward from above, while in its forward extension *a*⁴ it has corrugations *a*⁵, in line with the corrugations *a*³, but raised or pressed upwardly from below. This heel 70 plate, as usual, is provided with any suitable means whereby it may be secured to the foot, such as the slotted ears *a*⁶ to receive the usual straps, and is also slotted longitudinally, as at *a*⁷, to receive the locking bolt *c*. 75

The toe plate *b* has a downward bend, as at *b*², and is slotted in the bend, as *b*³, to permit the forward extension *a*⁴ of the heel plate to pass forward under the front portion *b*⁴ of the toe plate. The rearward extension *b*⁵ of the toe plate passes under the heel plate and is also corrugated longitudinally, as at *b*⁶, such corrugations being in line respectively with the corrugations *a*³ and *a*⁵ of the heel plate, and being sunken or 85 pressed down from above so as to fit upon the rearward corrugations *a*³ of the heel plate and be guided and steadied thereby. The rearward extension *b*⁵ of the toe plate is also slotted longitudinally, as at *b*⁷, 90 in line with the longitudinal slot *a*⁷ in the heel plate, to receive the locking screw *c*, the slotting of both plates permitting a greater length of longitudinal adjustment of the skate frame. 95

The clamping screw *c*, as before indicated, passes through the two slots *a*⁷ and *b*⁷, its head *c'* being slightly flattened on opposite sides, as shown at *c*² in Fig. 1, so as to stand between the forward corrugations *a*⁵ 100 of the heel plate and be held thereby from turning. The clamp *c*³, which is slipped on the lower end of the bolt *c* and is pressed upward by the nut *c*⁴, spans the ribs or cor-

rugations b^6 of the rearward extension of the toe plate and is itself slightly bent at the ends, as clearly shown in Fig. 5, to conform to the corrugations, so that it also is held from turning and has a wider bearing against the underside of the toe plate, thereby securing a firmer and more rigid clamping of the two plates.

The rear bracket d and the forward bracket e are each shouldered, at each side, as at d' and e' respectively, to form guides, respectively, for the rearward extension of the toe plate and for the forward extension of the heel plate.

The toe clamp bracket f is so constructed, in one piece, as to form a guide for the adjusting screw, a continuous guide for the clamps, and a guide for the forward part of the heel plate, being secured to the toe plate by two rivets f' only. To accomplish this result, it is formed in one piece as shown clearly in Figs. 2, 3 and 8, having head pieces f^2 which are riveted to the underside of the toe plate, depending clamp guides f^3 , a depressed flat portion f^4 which connects the head pieces and forms a guide for the forward extension of the heel plate, as shown in Fig. 3, and also to form lateral guides for the toe-clamps g and also carry a central lug f^5 which is turned down and is notched on its underside, as at f^6 , to engage the clamping screw h in the circumferential groove h' formed therefor. The toe-clamps g , which are threaded for engagement with the adjusting screw h in the usual manner, are supported by the outer clamp guides f^3 and are also guided in the continuous guide formed by the depressed bridge pieces f^4 , while the forward end of the heel plate which rests upon the bridge pieces is guided and steadied by the head pieces f^2 , passing through the guide way formed therefor between the bridge pieces and the toe plate above.

Each bracket, forward and rear, is formed as usual, the forward bracket e , for example, having downwardly and forwardly extending arms e^x , between which is received the axle bracket e^2 which carries the axle e^3 with its wheel e^4 . Between the axle bracket e^2 and the bracket e is interposed a cushion or bumper e^5 and the bumper cup e^6 , which has end flanges e^7 to retain the bumper e^5 in place and is itself usually secured in place by being riveted to the bracket e . In the present case, however, the rivets are dispensed with and the flanges e^7 are extended to form ears e^8 to overlap the arms e^x of the bracket e and so hold the bumper cup and the bumper from displacement.

It will be understood of course that the various features of improvement might be used independently of one another and are not necessarily combined in one structure, except so far as hereinbefore indicated, and

that details of construction might be changed without departing from the spirit of the invention.

I claim as my invention:

1. In a roller skate, the combination of a heel plate having its rear portion corrugated longitudinally with downwardly pressed corrugations and its forward extension corrugated longitudinally with upwardly pressed corrugations, a toe plate having its rearward extension corrugated longitudinally with downwardly pressed corrugations to fit upon the downwardly pressed corrugations of the heel plate, and means to clamp said plates together adjustably.

2. In a roller skate, the combination of a heel plate having upwardly pressed longitudinal corrugations, a toe plate having downwardly pressed longitudinal corrugations, one of said plates being slotted between the corrugations, a locking bolt passed through the plates between the longitudinal corrugations, and a clamp spanning the corrugations on opposite sides of the bolt.

3. In a roller skate, the combination of a heel plate, a toe plate, one of said plates being corrugated longitudinally and one of said plates being slotted, a locking bolt passed through the plates between longitudinal corrugations, and a clamp spanning the corrugations and conforming thereto.

4. In a roller skate, the combination of a heel plate, a toe plate, one of said plates having longitudinal corrugations and one of said plates being slotted, a locking bolt passing through the plates and having its head flattened at the sides to drop between the raised corrugations, and a clamp.

5. In a roller skate, the combination of a heel plate having raised corrugations in its forward extension, a toe plate having depressed corrugations in its rearward extension, one of said plates being slotted, a locking bolt passing through the plates and having its head flattened on opposite sides to drop between the corrugations of one of the plates and a clamp spanning the corrugations of the other of said plates and conforming thereto.

6. In a roller skate, the combination with the toe plate, toe-clamps and clamping screw, of a one piece toe-clamp bracket secured to the toe plate and having a depressed portion on which the toe clamps slide, and a central lug depending from the depressed portion to engage the screw.

7. In a roller skate, the combination with the toe plate, toe-clamps and clamping screw, of a one piece toe-clamp bracket secured to the toe plate and having depending terminal flanges to support the toe clamps, a depressed portion on which the toe clamps slide and a lug depending from the said depressed portion to engage the screw.

8. In a roller skate, the combination with

a foot plate, a bracket secured thereto and having depending arms, an axle bracket mounted between said arms, a bumper and a bumper cup interposed between the first 5 named bracket and the axle bracket, said bumper cup having flanges to retain the bumper and said flanges being extended to overlap the depending arms of said first

named bracket to retain the bumper cup in position.

This specification signed and witnessed this 20th day of May, A. D., 1909.

JOHN NUTTALL.
